UNITED STATES PATENT OFFICE.

RUDOLF MOHN, OF SULGEN, SWITZERLAND, ASSIGNOR TO WILLY MULLER, OF THAL, CANTON ST. GALLEN, SWITZERLAND.

LETTER-FRANKING MACHINE.

Application filed March 3, 1926, Serial No. 92,078, and in Switzerland December 15, 1925.

This invention relates to a machine for franking letters and the like or for stamping other documents, and consists in the provision of a rotatable drum in which a plurality of stamps are held so that they can be radially extended for cooperation with an inking roller and with an impression roller, the drum being rotated by means of a handle which is set for extending any particular stamp and for causing the impression roller to be applied to the stamp as the latter passes beneath it.

Fig. 1 of the accompanying drawings represents a front view of the machine casing with the drum and the cover plate for the inking mechanism removed, and

Fig. 2, a rear view of the open casing.

Fig. 3 is a front view, partly in section, of the drum, and

Fig. 4, a section of the drum taken on the line 4—4 of Fig. 3.

Figs. 5 and 6 are views at right angles to each other of the operating handle.

Fig. 7 is a front view of the complete machine, and

Fig. 8, a top view of the same.

The machine has a flat upright casing 2 which is closed at the back by a plate 1, the latter being integral with a supporting base 1^a. The casing is connected to the plate 1 by means of screws one of which is sealed. A shaft 16 is rotatably held in the casing 2 with one end projecting through the front wall of the same. On the projecting end of the shaft, a drum 3 is loosely mounted, and outside the latter there is a washer 3^a which is secured to the shaft by means of a nut 40 and a key whereby rotative relative displacement is prevented. A plate 39 is hinged at 39^a to the washer 3^a. The plate carries at the outside an operating handle 24 and at the inside a bevelled lug 41. By an adjustment of the handle plate 39 about its hinge and about the axis of the shaft 16 relative to the drum, the lug can be put into engagement with any of a circular series of apertures 42, made in the front wall 43 of the drum for coupling the latter to the handle and to the shaft. Opposite each slot 42 there is a stamp 46 recessed into the circumferential wall 57 of the drum. The stamp is radially adjustable so that it can be extended for use and it is connected by means of a stem to a pivoted lever 48 the free end of which projects into the slot 42

where it cooperates with the lug 41 of the handle plate, the arrangement being such that the stamp 46 is extended when the lug is inserted into the slot. A spring 49 (Fig. 3) holds the stamp normally in inoperative position within the drum.

An inking device is provided which consists of a ductor roller 4, an inking roller 6, and a messenger roll 5 which latter contacts alternately with the rollers 4 and 6. The inking roller is mounted direct on the casing 2 in position to contact with the extended stamp and carries a pinion 58 which meshes with teeth 59 cut into the circumferential wall 57 of the drum 3 so that the roller will be rotated together with the drum. The shaft of the ductor roller 4 is extended into the casing 2 where it carries a ratchet wheel 21 (Fig. 2). A bar 14 which is connected to and operated by a crank 15 on the shaft 16, is guided by means of a slot 19 on the ductor roller shaft and carries a pawl 20 which engages a ratchet wheel 21 so as to impart motion to the ductor roller through the shaft of the latter. A detent pawl 22 which also engages the ratchet wheel is mounted on the wall of the casing 2. The shaft 13 of the messenger roll 5 passes through a slot in the wall of the casing 2 and is secured to a lever 11 which is pivoted at 12 to the casing and held substantially parallel with the bar 14. A link 17 connects the bar 14 with the lever 11 so that the latter will be rocked by the former for changing the position of the messenger roll. A spring 18 acts on the lever 11 and tends to hold the messenger roll normally in contact with the inking roller.

An impression roller 34 is connected by means of its shaft 33 to a lever 30 which is pivoted at 31 to the inside of the casing wall, as shown in Fig. 2. A spring 32 acts on the lever and tends to pull the impression roller down against the drum 3. This is normally prevented by a cam 23 which is secured to the shaft 16 and which supports the lever 30 by means of a slide 25. The latter is guided in saddle pieces 26 and 27 on the casing wall and is fitted at the ends with anti-friction rollers 28 and 29. The cam is shaped so that it allows the impression roller to descend as the handle 24 passes together with the extended stamp.

There is a feeding table 8 connected to the casing 2 on a level with the top of the drum 3 opposite the impression roller 34.

Adjustable guides 9 and 10 can be set so as to restrict the table area to the size of the letter or document to be stamped, the documents being placed upside down on the table. 5
The stamps are all different and their nature or numerical value is shown on the drum outside the slots 42, as shown in Figs. 3 and 7. To select any particular stamp for operation, the handle 24 is coupled to the 10 drum, as previously described, opposite the particular stamp to be used, whereupon the drum is rotated by means of the handle in the direction of the arrow. As the stamp approaches the impression roller 34, a document is inserted between the latter and the 15 drum so as to be caught by the roller when the supporting slide 25 is retracted. The stamp, which is inked as it passes the roller 6, will then be applied to the document as it 20 passes under the impression roller.

A counting device 47 is arranged in the drum 3 for each stamp, the figures of the counters being visible in windows 44 in the drum wall 43. The operating spindle of 25 each counter is directed towards the stem of the stamp and carries a spur wheel 50 which is axially adjustable and which is held by a spring 48 against the stem of the stamp so that its position will be determined by the 30 latter. A bracket 51 (Fig. 1) secured to the casing 2 underneath the impression roller 34, carries a rack which is so arranged as to be engaged by any wheel 50 whose position is determined by an extended stamp. Thus 35 the counter of the extended stamp will be operated each time the stamp passes under the impression roller, the remaining wheels being held out of contact with the rack.

There is also a counter 38 which is always 40 operated for checking purposes independently of the stamp. For operating this counter there is a pin 54 arranged in the drum wall 43 behind each slot 42 parallel with the axis of rotation. The pins 54 are actuated by 45 springs which hold them normally in a forwardly projecting position. When the operating handle is coupled to the drum, the pin 54 which is situated at the selected slot 42, is pushed back by the plate 39, and in this 50 position, as it passes underneath the impres-

sion roller 34, it strikes against a lever 52 which then operates, by means of a shaft held in the wall of the casing 2 a lever 35 arranged inside the casing. The lever 35 is connected by a link 36 to a lever 37 which 55 rocks the spindle of the counter 38. Thus, while the impressions of the different stamps will be recorded individually by the counter 47, the total impressions made will be recorded by the counter 38. 60

To prevent the drum from being rotated in the wrong direction, a pawl 55, held by a pivot on the drum, slides over the teeth of a ratchet wheel 56 connected to the casing 2. 65

I claim:

1. A letter franking machine comprising a casing, a rotatable shaft held in said casing, a drum mounted loosely on said shaft, stamps mounted in the circumference of said drum so that they can be radially extended, 70 a crank handle hingedly secured to the shaft, means cooperating with said handle for extending any particular stamp, means whereby the handle is coupled to the drum when a stamp is thus extended, means for inking 75 the extended stamp, an impression roller arranged on the casing for cooperation with the extended stamp, means permitting the feeding of documents between the impression roller and the drum, and means controlled 80 by said shaft for applying the impression roller to the drum as the extended stamp passes. 85

2. A machine according to claim 1 in which the operating means for the impression roller comprises a cam connected to the machine shaft, a spring-actuated lever pivoted to the casing and holding the roller, and a slide which supports the lever on said cam. 90

3. The structure claimed in claim 1 in addition to counters arranged in the drum close to the different stamps, means causing the counter of an extended stamp to be operated at each complete revolution of the drum, a 95 checking counter connected to the casing, and means for operating said checking counter at each impression.

RUDOLF MOHN.
